Primary Examiner—Mitchell Siegel

(57) **CLAIM**

The ornamental design for a golf towel, as shown and described.

DESCRIPTION

FIG. 1 is a perspective view of a golf towel showing our new design; the broken line showing is included for the purpose of illustrating and forms no part of the claimed design.

FIG. 2 is a front elevational view thereof;

FIG. 3 is a rear elevational view thereof;

FIG. 4 is a top elevational view thereof;

FIG. 5 is a left side elevational view thereof; and,

FIG. 6 is a right side elevational view thereof.
